SURGICAL BANDAGING

Eugen Sander, Munich-Menterschwaige,
GermanyApplication May 10, 1930, Serial No. 451,442,
and in Germany May 10, 1929

1 Claim. (Cl. 128—154)

My invention relates to an improved surgical dressing, and its object is to provide a dressing which may be easily applied to and removed from a wound with a minimum of discomfort to a patient.

I accomplish this object by constructing the dressing of an orificed layer of adhesive plaster, a ring of resilient material about the orifice adjacent that face of the plaster to be applied to the wound, a layer of dressing material covering the orifice in the plaster and a second layer or piece of plaster over the layer of dressing material.

One embodiment of the invention is illustrated in the accompanying drawing, in which

15 Fig. 1 is a sectional view of my improved surgical dressing, and

Fig. 2 shows it as seen from above.

A plaster 3 pasted on the wounded part 1 of the body 2 is provided with an opening 4 in reach 20 of the wound 1. The opening 4 is bounded by a ring 5 of resilient material. Above the opening 4 of the plaster 3 there is pasted a covering 6 which carries a layer 7 of dressing material.

In using the dressing the plaster 3 is applied 25 to the body so that the opening 4 coincides with the wound 1. Then the covering piece 6 carrying the dressing 7 is placed upon the plaster after the wound has been treated with the necessary drug.

30

For treating the wound it is merely necessary to remove and renew only the covering piece 6 which causes no pain to the patient because this piece is only applied to the plaster 3. The covering piece 6 is prevented by the ring 5 from touching the wound, and consequently the wound which is probably already covered with a scab or healing cannot be torn open again by the taking off of the covering piece 6. The distance of the covering piece 6 from the wound offers the 65 further great advantage that the healing procedure is much quicker and easier.

Consequently the wound 1 can be surveyed and cleaned in the most simple manner as often as required without any pain or other discomfort 70 to the patient.

What I claim is:

A surgical dressing comprising an adhesive plaster having an opening therein, a ring of resilient material engaging a face of the plaster 75 about said opening, a layer of dressing material overlying said opening on the opposite face of the plaster and a second adhesive plaster overlying said dressing material and removably attached to the first plaster.

EUGEN SANDER.
